ROTARY ENGINE.

APPLICATION FILED JAN. 22, 1907.

2 SHEETS—SHEET 2.

UNITED STATES PATENT OFFICE.

ROBERT MOND, OF LONDON, ENGLAND.

ROTARY ENGINE.

No. 869,100.

Specification of Letters Patent.

Patented Oct. 22, 1907.

Application filed January 22, 1907. Serial No. 363,506.

To all whom it may concern:

Be it known that I, ROBERT MOND, a subject of the King of Great Britain, and residing at 27 Berkeley Square, in the county of London, England, chemical engineer, have invented certain new and useful Improvements in Rotary Engines, of which the following is a specification.

There is a well-known type of rotary fluid pressure engine wherein a revolving piston forms the middle member of a universal joint connecting two inclined shafts. By my invention an engine of this type is operated as an internal combustion engine, instead of being worked as hitherto, by a fluid supplied under pressure. For this purpose it is essential to supply the engine with suitable valves, cams and cam shaft or their equivalent, and these may be such that the engine may operate on the 4-stroke or 2-stroke cycle.

Thus according to my invention the engine is provided with a distribution block with ports for passage of the combustible, the supporter of combustion and if necessary also for the exhaust, and with a valve block having corresponding ports. It is generally also necessary that there should be a set of valves preferably of the mushroom type controlling the inlet and outlet of the respective chambers into which the working compartment or compartments of the engine is or are divided.

A system of cooling those parts of the engine which become heated by the products of combustion is essential and preferably consists of passages permitting circulation of a cooling fluid through the distribution block and valve block and around the heated parts.

Preferably the shaft which in the fluid pressure engines of this type is called the main shaft is hollow, to permit of the cam shaft extending through it into the valve block. For a 2-stroke cycle the cam shaft may be held stationary but for a 4-stroke cycle it should be geared to rotate at half the speed of the main shaft. This gearing may be through a lay shaft, which may also be the shaft for transmitting the power. Or the shaft which is at an angle to the main shaft hereinafter called the second shaft, may extend through the casing and act as the power shaft, in which case a uniform transmission of power from the shaft may be secured by a flexible coupling.

Certain details of construction also form a part of my invention as will be described with reference to the accompanying drawings.

Figure 1 is a longitudinal vertical section of one form of engine constructed according to my invention. Fig. 2 is a part sectional view showing the rotating cylinder in transverse section. Fig. 3 is a cross section on line -3-3 of Fig. 1. Fig. 4 is a view showing the inlet and

outlet ports. Fig. 5 is a longitudinal section of the rotating cylinder.

The engine is of the type described for actuation by fluid pressure in specification to British Patent No. 18402 of 1889.

The main shaft 1 is keyed to the valve block 2 which is preferably integral with the cylinder 3 and in any case turns therewith. The bearing 1^a for the shaft 1 and the bearings 6 and 7 for the second shaft 4, which rotates at an angle to the shaft 1, are carried by the fixed casing 11. The piston 5 is pivoted to the shaft 4 so as to rotate therewith and carries trunnions which turn in bearings in the ends of the cylinder 3. A cylindrical surface on the piston bears against a central abutment 8 in the cylinder so that the latter is divided into two working chambers 9 and 10 rendered gas tight by suitable packing on the abutment and on the sides of the piston, by the oscillation of which these chambers alternately increase and decrease in capacity. At the end 11^a of the casing 11 through which the main shaft passes is a fixed distribution block 12 containing a number of concentric annular passages 13, 14, 15, 16 communicating respectively with ports 17 and 17^a, 18 and 18^a, 19 and 19^a, and 20 and 20^a, (Fig. 4) in the valve block 2.

Within the valve block are four suitable valves operated automatically or by any suitable mechanism. The valves here shown are of the mushroom type and are set in chambers which communicate in pairs with the chambers 9 and 10 of the cylinder. For instance the chambers of valves 21 and 24 may communicate with chamber 9 and those of valves 22 and 23 with chamber 10. Ports 17 and 17^a communicate with the spaces 36, 36 beneath valves 21 and 23 respectively, ports 18 and 18^a, with the spaces 33, 33 beneath valves 22 and 24 respectively, and ports 19 and 19^a with the annular chamber 32, 32 respectively.

The valves are controlled by a cam shaft 25 which extends through the hollow shaft 1 into the valve block where it carries cams 37, 38 which lift the valves against the pressure of springs 42; either directly or through the pivoted arms 39, 40 as the cam shaft is revolved from shaft 1 at half the speed of the latter through the gear wheels 26, 27, 28, 29, of which 27 and 28 are keyed to a lay shaft 30.

Assuming that the engine is working on the Otto cycle, when valve 22 begins to lift air passes from the atmosphere through annular passages 14 and port 18 to the space beneath the valve and past the latter to chamber 10 the capacity of which is just beginning to increase. When the valve has performed a small portion of its stroke it lifts a supplementary valve 34 which until then has closed the annular chamber 32, whereupon gas

passes from an external supply through passage 15 port 19 and chamber 32 and mixes with the air in space 33, so that for the rest of the intake period a mixture of gas and air enters chamber 10 until the latter has attained 5 its maximum capacity which happens during approximately one half revolution of shaft 1. During the next half revolution the gaseous mixture in chamber 10 is being compressed, and when the chamber is at or about at its minimum capacity the mixture is ignited by any 10 well known means. The next half revolution is the working stroke and just before it is ended the valve 23 is opened, and the products of combustion are expelled during the next half revolution through this 15 valve, space 36, port 17 and passage 13 into the atmosphere. It will be readily understood how a like cycle occurs in chamber 9 giving two working strokes for every two revolutions of the shaft 1.

For the purpose of cooling the valve block and cylinder, water enters through passage 16 and takes the 20 following course:—Entering the valve block through ports 20 and 20^a, (Figs. 1 and 4) it passes through passages 43 and 43^a, into passages 44 and 44^a. From each of these passages the water diverges, flowing through passages 45, 46, 47, 48, and 45^a, 46^a, 47^a, 48^a, respectively (Fig. 3) over half the valve covers, and thence through passages 49, 49^a. The latter communicate with passages 50 and 50^a which extend round a large portion of the cylinder wall and merge into passages 51, 51^a, extending over practically the whole of the cylinder covers. From the last named passages the water 30 passes through the interior of the abutment 8 by passage 52, and the two portions of cooling water now converge at 53 to pass through passage 54, cooling the rest of the cylinder wall and the valve block. From 54 the 35 course is through passages which lead respectively to 56, 57, 58, 59 and 56^a, 57^a, 58^a, 59^a. The water flowing through these cools the rest of the valve covers and finally escapes through passages 55 and 55^a into the external casing 11 whence it is drained by pipe 60.

40 For the purpose of cooling the piston a tight joint is made by fitting a plate 61 with a central opening to the shaft 4 to the cylinder so that it rubs lightly against the annular surface 63. Into the space between the cover 62 of the casing and piston 5 oil or an emulsion of oil and 45 water is passed through pipe 64, leaving by pipe 66; this liquid flows or is splashed over the parts to be cooled and lubricated.

For lubricating the valve motion, oil under pressure 50 enters through pipe 67 into a fixed gland 68 to flow through the cam shaft into the cam chamber 69, the excess of oil draining through a small passage in the valve block into the casing 11. It is preferable to lubricate the surface of contact between the abutment 8 and the piston by a separate oil supply which flows through 55 pipe 70 into a fixed gland 71 and passes through a hole 72 drilled in the shaft, and thence through 73 and 74 of which the latter crossing the water passages 54 and 52 by means of a tube delivers the oil to the said surface.

Collars 75, 76, 77, 78, 79 and 80 are provided for adjusting the rotating parts relatively to the bearings which carry them and to the rubbing face of the distribution chamber.

In Fig. 1 the second shaft 4 is shown in a horizontal

position for use as the driving shaft; a suitable flexible coupling 31 should transmit the motion of this shaft to 65 any gear through which it may do work, in order to avoid trouble arising from the fact that shaft 4 does not rotate uniformly, whereas the shaft to which it is flexibly coupled must rotate uniformly if it is to do useful work. It is generally more convenient however 70 to arrange the engine so that the lay shaft 30 is horizontal and the second shaft 4 inclined. The lay shaft can then be used as the driving shaft.

If the engine is to be operated on a two-stroke cycle the cam shaft is fixed, and thus operates the valves once 75 in each revolution instead of once in every two revolutions. The gas and air must be supplied under sufficient pressure to allow a scavenging charge of air to pass through the chamber 9 and 10 before the combustible mixture is admitted. The lay shaft being no 80 longer required shaft 1 may be the driving shaft, or shaft 4 as before explained.

It is obvious that the engine may be operated as an oil engine, in which case only one set of inlet ports for the carbureted air is required, instead of separate 85 ports for gas and air.

Having now particularly described the nature of my said invention and the best means I know of carrying the same into practical effect, I claim:—

1. In a rotary internal combustion engine a revolving cylinder, a revolving piston oscillating in the cylinder, a valve block revolving with the cylinder, a distributing block in contact with said valve block, and ports in the valve block for the admission of air and gas and for the expulsion of products of combustion, said ports being in communication with passages in the distributing block, substantially as described.

2. In a rotary internal combustion engine, a revolving cylinder, a revolving piston oscillating within the cylinder, a valve block revolving with the cylinder, valves in said valve block, a cam shaft coaxial with one of the two shafts of the engine operating said valves, a distributing block in contact with said valve block, and ports in the valve block for the admission of air and gas and for the expulsion of products of combustion, said ports being in communication with passages in the distributing block, substantially as described.

3. In a rotary internal combustion engine, a revolving cylinder, a revolving piston adapted to oscillate in the revolving cylinder, a valve block revolving with the cylinder, valves in said valve block operated by a cam shaft coaxial with one of the two shafts of the engine, a lay shaft geared with said engine and same shaft, a distributing block in contact with said valve block, ports in the valve block for the admission of air and gas and for the expulsion of products of combustion, said ports being in communication with passages in the distributing block, substantially as described.

4. In a rotary internal combustion engine, a revolving cylinder, a revolving piston oscillating in the revolving cylinder, a valve block revolving with the cylinder, a distributing block in contact with said valve block, ports in the valve block for the admission of air and gas and for the expulsion of products of combustion, such ports being in communication with passages in the cylinder, the valve block and distributing block for the circulation of a cooling fluid, substantially as described.

5. In a rotary internal combustion engine, a revolving cylinder, a revolving piston oscillating in the revolving cylinder, a valve block revolving with the cylinder, distributing block in contact with said valve block, ports in the valve block for the admission of air and gas and for the expulsion of products of combustion, said ports being in communication with passages in the distributing block,

and a chamber at the back of said piston for the reception of oil, or an emulsion of oil for the cooling and lubricating the piston, substantially as described.

6. In a rotary internal combustion engine, a revolving cylinder, a revolving piston oscillating in the revolving cylinder, a valve block revolving with the cylinder, valves in said valve box, a cam shaft coaxial with one of the two shafts of the engine, operating said valves, a distributing block in contact with said valve block, ports in the valve block for the admission of air and gas and for the explosion of products of combustion, said ports being in commu-

nication with passages in the distributing block, and passages through the shafts of the engine, the cam shaft and valve block for admission of oil to the parts of the engine requiring lubricating, substantially as described.

In testimony whereof I have signed my name to this specification in the presence of two subscribing witnesses.
